AUTOMOBILE V ENGINE SYMMETRICAL
MANIFOLD

Jules Haltenberger, Rancho Santa Fe, Calif.

Application April 24, 1950, Serial No. 157,734

8 Claims. (Cl. 123—52)

1

This invention relates to V engine manifolds, and particularly to an inlet manifold for eight cylinder V engines as used in automobiles and the like, a purpose being to provide an intake manifold which will be substantially symmetrical in construction and in functioning and operation, this being a continuation in part or extension of my co-pending application Serial No. 122,474, filed October 20, 1949.

The inlet manifold of an automobile, though frequently neglected in the advancement of science, plays an important part in cold engine starting gas distribution, equal cylinders fillings, vibration, acceleration, and over all economy.

A usual V engine has opposite rows of longitudinally disposed cylinders and is provided with a usual two level inlet manifold unit.

The upper and lower level manifolds of the unit operate independently. Each of them comprises a generally longitudinally extending duct and associated crosswise ducts arranged to reach the cylinders in opposing rows. Each of the longitudinally extending ducts are provided with an inlet passage disposed in the longitudinal center of the duct, or a pair of longitudinally disposed inlet passages adjacent to and at each side of the duct center.

All manifolds applicant is aware of have variant duct angles and variant length of inlet ducts. In certain existing applications the duct length leading to one cylinder has nearly twice the length of the duct leading to another cylinder. They also include harmful Y connections and harmful duct intersections wherein a duct engages an intermediate portion of an associated duct.

It was proposed to provide one end of a usual lengthwise duct with a crosswise duct having equal length arms, it is here proposed and is the object of my invention to form and shape the generally longitudinally extending ducts for the adoption at each of their respective ends to substantially right angularly disposed two-direction crosswise ducts, having substantially equal length arms. Thereby, all the angular dispositions and lengths of all ducts, as measured from the longitudinal duct center to each and every cylinder is substantially duplicated.

A further object is to provide each of the ends of the lengthwise ducts with substantially right angularly disposed two-direction crosswise ducts having substantially equal length arms, and including upstanding substantially flat mixing walls on inner sides of the outer walls of the crosswise ducts, each disposed in line with and in length

2

substantially twice the width of the outlet end of the respective lengthwise duct.

A further object is to accelerate the gas travel or passage through the double H manifold by aerodynamic section turning vanes.

Further objects will appear as the description proceeds.

Referring to the drawings: Fig. 1 is an end and more or less diagrammatic elevation of a usual V engine showing the inlet manifold embodying my invention; Fig. 2 is a plan view of the manifold with parts broken away here shown in a fragmentary larger scale; Fig. 3 is a transverse section substantially on line 3—3 of Fig. 2; Fig. 4 is a fragmentary plan view of the manifold shown in Figs. 1, 2 and 3 wherein the connections of the ducts are modified; Fig. 4A is a modification of a part shown in Fig. 4; Fig. 5 is a section substantially on line 5—5 of Fig. 4; Fig. 6 is a fragmentary plan view with parts in section showing a further modification of the ducts connections and illustrating twin lengthwise ducts; Fig. 7 is a section substantially on line 7—7 of Fig. 6.

Referring to Figs. 1, 2 and 3, it will be seen that a usual V engine 8 is provided with superimposed double H manifold casting generally at 9, it is composed of an upper level H leading to the manifold outlets for cylinders 1, 7, 6 and 4, and a lower level H, leading to the manifold outlets for cylinders 8, 3, 5 and 2.

The upper level H is formed of an inlet passage 10 and thereto connected lengthwise duct 11 and crosswise two-direction duct having substantially equal length arms 12 forming a substantially right angularly disposed intersection. The inner surface of wall 13 of duct 12 is at right angles to duct 11, and is smooth and straight in length M, that corresponds to substantially twice the width of duct 11, thereby serving as an upstanding gas mixing wall.

Opposite to duct 11, a lengthwise continuation slightly bent duct 14 is formed, which is also provided with a crosswise two-direction duct having substantially equal length arms 15 forming an intersection and substantially right angular mixing wall 13 a duplicate in length to M.

It is important to note that, as is clear from Fig. 1, the gas travel distance from the center of passage 10 to each center of the manifold outlet ports 16 leading to the respective cylinders 1, 7, 6 and 4, is substantially exactly the same.

The lower level H manifold, leading to the manifold outlets 16 for cylinders 8, 3, 5 and 2 is substantially an exact duplicate of the upper level manifold, except that it is reversed or turned in

a 180 degrees parallel plane and is connected to the adjacent inlet passage 10', therefore the indicating numerals are duplicated with a prime.

The upper level H having substantially equal length gas passages, and the lower level being 180 degrees turned duplicate of the upper, forms a V engine manifold of complete symmetry for equal gas distribution to all cylinders.

As is clear from the drawings, the inlet passages 10 and 10' are surrounded with a usual exhaust gas heating jacket 17, having exhaust gas communication ports 17' in the usual manner.

The gas mixture flowing through the upper level ducts 11 or 14 slams or impinges against right angular mixing walls 13 where the heavier mixture droplets cover the wall surface for a subsequent "surface carburation," whereas, the lighter mixtures fill the respective cylinder. In the lower level ducts 11' or 14' the action is exactly the same as in the upper level ducts.

Applicant's co-pending patent application, hereinabove identified, points out the advantages of increasing the cylinder filling by the ram effect of the inlet manifold, accomplished by increasing the flowing mixture speed and effective ram length by the use of aerodynamic section turning vanes. The use of turning vanes for this effect is illustrated in Figs. 4 and 5, as applied to a double H manifold.

Here, the double H manifold is substantially a duplication of the manifold described in intersection with Figs. 1, 2 and 3, excepting the connections in between all the lengthwise and crosswise ducts, therefore, for simplicity of presentation the indicative numerals are duplicated.

As is clear from the drawing, the upper wall 20 of the crosswise duct 12 is provided with a machined opening 21, for the adoption of a preferably die cast metal or plastic plug generally designated at 22, arranged to be secured to the manifold as by screws 23. The plug is formed of a flanged wall 24, having protruding aerodynamic section turning vanes 25.

For gas flow duplication and manufacturing facility the plugs at the upper and lower levels can be identical pieces. The desired width of the ducts imposed certain limitations as to the plug location in wall 20, therefore, plug wall 24 is also provided with a substantially flat mixing wall 13'.

In operation, the aerodynamic section turning vanes increase the gas speed and the effective ram length of the manifold, and hold the gas mixture to more uniform consistency and permits the use of a lighter mixture, as a greater part of the mixture is aerodynamically directed to the exit port. The application of these vanes is inexpensive as all plugs can be identical. It will be noted, that all the turning vanes disposed in the intersection of the lengthwise duct and two-direction crosswise duct form clusters and have substantially correct aerodynamic sections, they all terminate in thin edges to reduce drag and here shall be referred to as aerodynamic section. All the vanes have materially less width (measured from the leading edge to the trailing edge) than the width of either of the associated ducts.

When it is desired to further increase the ram effect, this may be accomplished as illustrated in Fig. 4A where a plug generally indicated at 22' is provided with filling wall 13''. Here this wall is curved in further response to aerodynamic teachings.

For certain applications, when it is desired to increase the ram effect of a double H manifold to optimum while retaining the desired symmetry

and all perpendicular outlets, a modified embodiment is illustrated in Figs. 6 and 7. Here, excepting the lengthwise ducts and crosswise ducts intersections the manifold is identical to the one 5 described in connection with Figs. 1 to 3 inclusive.

As is clear from the drawings, the upper level inlet passage 10 (indicated by a chain line) leads to a pair of associated lengthwise ducts, 26 and 27 with a parting wall 28 having a blunt leading 10 edge 29 in between. At the intersection of these ducts with crosswise ducts 12 the upper wall 20' of duct 12 is provided with a machined opening 21' for the reception of a die cast metal or plastic plug generally indicated at 22'' that can be secured to wall 20' as by screws 23. Plug 22'' is formed of a flanged wall 24' having protruding aerodynamic section direction changing vanes 25', where the leading vane width is less than half the width of ducts 26 or 12 and a protruding 15 partition wall 28' terminating in filler curves 13'''.

Opposite ducts 26 and 27 a pair of associated ducts 30 and 31 are provided, leading to and intersecting with crosswise ducts 15.

For equal gas flow characteristics and manufacturing simplification the two plugs at the upper level are identical with the plugs of the lower level.

The here presented manifolds provide for substantially equal length gas passages through their carefully planned symmetry. All crosswise passages are perpendicular to the associated lengthwise passage. All lower level ducts are the duplicates of the upper level ducts except being turned 30 a half circle around in a parallel plane.

Applicant believes that uniform cylinder filling is contingent on uniform duct angles and passages with or without turning vanes. After meeting the equilength condition, the application of 35 turning vanes further accentuates the values of equilength.

V engines though long in use, presently are gaining in the automotive field, because of their desired short length, and other advantages; further, all manufacturers have the rear engine application in mind, where the need for a short 40 engine is a precondition.

Whereas Figs. 2, 4 and 5 indicate the simplest form of manifolds, wherein each of the lengthwise ducts are provided with only one carburetor 50 inlet passage, the benefits of this invention will equally accrue in manifolds where the lengthwise ducts are provided with the well known pair of longitudinally disposed adjacent inlet passages, 55 for the adoption of the well known "Quadri-Jet" carburetor.

It is important to note, that here every lengthwise duct terminates in substantially right angular terminal crosswise duct, or two substantially 60 half length ducts, and each half at an identical angle to the lengthwise duct, this, to avoid the grave error wherein one crosswise terminal duct half is disposed at a different angle to the lengthwise duct than the other half, thereby favoring 65 the gas flow of one at the expense of the other. It will also be noted that applicant eliminates any crosswise ducts that "tap in" at an intermediate point between the lengthwise duct ends, as they have no range in performance.

In this patent application, and appended claims, "lengthwise" shall mean the generally accepted interpretation of the word, wherein all the lengthwise ducts are disposed generally aligned with the aligned rows of engine cylinders.

While I have herein shown and described only

certain specific embodiments of my invention and have suggested only certain possible modifications, it will be appreciated that many changes and variations can be made to suit particular conditions and embodiments of use, without departing from the spirit and scope of my invention.

What applicant claims as his invention:

1. In a V engine inlet manifold, an inlet passage, an associated lengthwise duct, a pair of associated crosswise ducts forming two connections, and directional turning vanes carried by insertable plug means in said connections.

2. In a V engine inlet manifold, an inlet passage, a pair of associated lengthwise ducts, a pair of associated crosswise ducts forming two connections, and directional turning vanes in said connections carried as parts of insertable and interchangeable plugs.

3. In a V engine having opposite rows of cylinders, an inlet manifold including a pair of adjacent independent inlet passages in association with a pair of longitudinally extending ducts, said ducts extending substantially equidistantly from their respective inlet passages in two opposite directions, and all of said ducts terminating in substantially right angularly disposed two-direction crosswise ducts having substantially equal length arms, the ends of each crosswise duct substantially reaching the cylinders in the opposing rows.

4. In a V engine inlet manifold including a pair of adjacent independent inlet passages in association with a pair of wide lengthwise ducts, said ducts terminating in two-direction substantially right angularly disposed crosswise ducts having substantially equal length arms, and upstanding substantially flat mixing walls on the inner sides of said crosswise ducts disposed in line with and in length substantially twice the width of the outlet ends of said lengthwise ducts.

5. In a V engine inlet manifold a lengthwise duct terminating in a two-direction crosswise outlet duct, said ducts forming an intersection, an upstanding substantially flat mixing wall on the inside of said crosswise duct disposed in line with the outlet end of said lengthwise duct, and aerodynamic section turning vanes in laterally

spaced relation in said intersection exposing therebetween the whole midportion of said upstanding mixing wall.

5 6. In a V engine inlet manifold a lengthwise duct terminating in an angularly disposed substantially equal width outlet duct, said ducts forming an intersection, and an aerodynamical section direction changing vane of materially less width than either of said ducts disposed in said intersection.

7. In a V engine inlet manifold, a lengthwise duct terminating in an angularly disposed substantially equal width two-direction outlet duct, said duct forming an intersection, and a cluster of aerodynamical section direction changing vanes all of materially less width than either of said ducts, disposed in said intersection.

8. For a V engine having opposite rows of cylinders, an inlet manifold including a pair of adjacent independent inlet passages in association with a pair of longitudinally extending ducts, said ducts extending from their respective inlet passages in two opposite directions, and all of said ducts terminating in substantially right angularly disposed two-direction crosswise ducts having substantially equal length arms, the ends of each crosswise duct substantially reaching the cylinders in the opposing rows.

JULES HALTENBERGER.
